UNITED STATES PATENT OFFICE.

ELBERT F. WILCOX, OF KANSAS CITY, MISSOURI.

CONCRETE PAVEMENT.

1,134,306.

Specification of Letters Patent. Patented Apr. 6, 1915.

Application filed February 16, 1914. Serial No. 818,827.

To all whom it may concern:

Be it known that I, ELBERT F. WILCOX, a citizen of the United States, residing at Kansas City, in the county of Jackson and State of Missouri, have invented certain new and useful Improvements in Concrete Pavements; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to concrete pavement, and more particularly to a method of laying such pavement to provide a suitable expansion joint and a smooth and even surface on either side of the joint, and which is adapted to prevent abrasion of the concrete at the joint, and the cracking of the pavement between the joints.

In order to fully explain the joint and its method of construction, I have illustrated various steps in the construction of the pavement in the accompanying drawings, wherein:

Figure I is a perspective view of a pavement constructed according to my invention and illustrating the use of a straight edge in combination with screeds set across the roadway to divide the sections of pavement, and to secure uniform and even curvature of the pavement. Fig. II is a vertical section of a portion of the pavement on the line II-II, Fig. I, indicating the construction and use of the screed. Fig. III is a view on the same line, showing the divided concrete sections after the screed is removed. Fig. IV is a view on the same section after the dividing channel, formed by removal of the screeds has been filled with fine concrete and an expansion member showing the original projection of the expansion member and the beaded edges of the concrete. Fig. V is a view on the same line, showing the completed joint.

Referring more in detail to the drawings:—In constructing the pavement with my improved method, screeds, preferably formed of planks two inches in thickness and tapering from top to bottom in order to form a wedge-like structure, are arranged transversely in the roadway between the curbing, with the small edge down and with the screeds spaced so as to form pavement

sections of such width that the usual expansion and contraction may occur without cracking the slabs; the upper edges of the screeds being curved on a line corresponding to the drain line of the street, so that when green concrete is filled in between the screeds, a straight edge 2 may be moved over the upper edges of adjacent screeds to smooth and shape the surface of the roadway. With the screeds in place, concrete is flowed thereinto to fill the spaces therebetween. The straight edge is then moved over the surface of the concrete and guided over the upper curved edges of the screeds to shape the surface of the roadway. After the surface is shaped and the concrete has set sufficiently to hold its shape, the screeds are removed by a lifting tool, of any suitable construction, which preferably comprises a hook (not shown) that may depend into a socket 4 opening through the top of the screed and engage a cross-rod 5 in said socket in order that the screed may be lifted out of the concrete without unduly disturbing the surface of the roadway, and particularly without chipping the corners of the concrete beds adjacent to the channel formed by the removal of the screeds. After the screeds have been removed, an expansion strip 6, preferably formed of pitch, is placed in the channel with its upper edge projected above the surface of the roadway, and the channel filled at both sides of the strip with fine concrete 7, which may be worked with a tool. With the expansion block and fine concrete in place, the latter is tamped in place and its upper surface tooled to form recesses 8 adjacent to the block. After the recesses are formed and the concrete, both coarse and fine, set, the exposed edge of the expansion block is mashed down into the recesses 8 to form a smooth surface for the roadway.

With my improved method, the surface of the roadway may be sloped to the desired drain curvature by moving the straight edge transversely across the roadway from curb to curb, in contact with the curved edges of the screeds, and the expansion joints built in after the slabs have set. By forming the joints of an expansion strip and fine concrete, a workable material is provided which welds into the coarser body of the slab and enables me to shape the edges of the slabs to receive the malleable expansion member, and thereby obviate uneven edges, that may afterward chip or wear.

Having thus described my invention, what I claim as new therein, and desire to secure by Letters-Patent, is:—

The method of constructing a concrete roadway, consisting of setting screeds, filling the spaces between the screeds with coarse concrete, drawing a straight edge over the exposed edges of the screeds, to smooth the surface of the concrete, removing the screeds to provide channels between concrete slabs, spacing an expansion member in the channel, filling the spaces on op-

posite sides of the expansion member with fine concrete, tooling the upper surfaces of the fine concrete along the expansion member to form recesses, and mashing the expansion member into said recesses. 15

In testimony whereof I affix my signature in presence of two witnesses.

ELBERT F. WILCOX.
